UNITED STATES PATENT OFFICE.

PAUL REVERE ODELL, OF BUTTE, MONTANA.

SLEEPING-CAR BERTH.

1,233,113.

Specification of Letters Patent. Patented July 10, 1917.

Application filed March 2, 1917. Serial No. 151,937.

To all whom it may concern:

Be it known that I, PAUL REVERE ODELL, a citizen of the United States, and a resident of Butte, in the county of Silverbow 5 and State of Montana, have invented an Improvement in Sleeping-Car Berths, of which the following is a specification.

My invention is an improvement in sleeping car berths, and has for its object to provide a section wherein a dressing aisle may 10 be provided in connection with each of the berths.

In the drawings:

Figure 1 is a perspective view showing 15 the improved berth with the dressing aisles open.

Fig. 2 is a similar view showing the berths disassembled, and arranged as seats.

Fig. 3 is a section on the line 3—3 of 20 Fig. 1.

Fig. 4 is an end view of one of the spring controlled reels.

Fig. 5 is a perspective view of the base of the dressing aisle for the upper berth.

In the present embodiment of the invention, the lower berths are composed by the seat frames, to be described, and U-shaped frames 2, the said frames 2 being arranged between the seat frames. Each 25 seat frame is substantially chair-shaped, consisting of the seat proper 1, and a back 3. The seat frames are similarly arranged, that is with the seat portions extending on the same sides of the backs. The seat portion 30 of each seat frame provides one seat, and the other seat on the opposite side of the back is provided for by the adjacent U-shaped frame 2, and a seat cushion 4.

These seat cushions 4 are hinged to supports 5 on the backs 3, the upper edges of the supports 5 being at the level of the upper surface of the seat portions 1 of the seat frames. These cushion seats 4 may fold upwardly into the position of Fig. 1, 45 where their upper edges will contact with the lower edges of the head cushions 6, or downwardly into the position at the right of Fig. 2, where they rest upon U-shaped frames 2. Each of the seats in connection 50 with the seat portion 1 of the seat frame consists of a seat cushion 7, a back cushion 8, and a head cushion 6, the said cushions being connected with the seat and the back, respectively.

The seat cushions 7 are mounted to slide on the seat frames, each cushion having on

its under side a pair of plates 9 provided with longitudinally extending slots which are engaged by pins on the seat frames. Thus the mattress of each lower berth is 60 composed of one seat cushion 4, one seat cushion 7, and two back cushions 8. In order to form the seats into berths, each seat cushion 4 is turned down onto the adjacent U-shaped frame, as shown at the left 65 of Fig. 1. The adjacent seat cushion 7 is then pushed laterally until it contacts with the adjacent edge of the seat cushion 4, the seat cushion 7 now resting upon the edge of its seat frame and the U-shaped frame. 70 Two back cushions are then arranged upon the seat of the seat frame.

When the occupant arises, he or she will swing up the seat cushion 4 into the position shown at the right of Fig. 1, and there 75 will thus be left a clear aisle for dressing, of a size approximately twenty inches wide by three feet deep. The occupant may sit upon the seat cushion 7 and there will be ample head room.

Each upper berth is composed of a large cushion 10 and a smaller cushion 11, and the said cushions are hinged to the car in the usual manner, to swing up into the closed position or down into horizontal position. These cushions are normally held in folded position by means of flexible members 12, and 13, respectively, the flexible members in the present instance being 80 chains. These chains connect at one end 85 to the cushions, and at the other end they wind upon spring controlled reels 14, which are journaled in brackets 15 secured to the car wall, and the chains pass over pulleys 16 before reaching the reels. When these 90 cushions are folded down into horizontal position, they rest at their remote ends on sliding supports 17, these supports being in the form of plates, having ribs 18 at their lower edges which slide in grooves 19 in 95 the tops of the backs.

Each support is of approximately half the width of the berth, so that it may be pushed back out of the way when the berths are not made up. Each support has connected to the rear end thereof a strip 20 of fabric material of the same width as the support, and at its rear end each strip is secured to the car wall or to the berth support. 105

The inner ends of the cushions 10 and 11 at their outer edges are upheld by bars 21. 110

Each of these bars 21 is provided at its upper end with a transversely extending slot 22 and at its lower end with a longitudinally extending slot 23. These slots are adapted to receive buttons on the seat frames and on the edge of the cushion 10, and they are of a length to hold the adjacent end of the cushion 10 at the proper height to make said cushion horizontal. The cushion 11 is supported by the adjacent support 17, and by the mechanism shown in Fig. 5.

This mechanism comprises a foot plate 24 having at one edge thereof a back plate 25. A side plate 26 is hinged to the foot plate 15 near one edge, the end of the side plate contacting with the back plate 25 when the side plate is unfolded as indicated in full lines in Fig. 5. It will be noticed that both the back plate and side plate are spaced from 20 the adjacent edges of the foot plate. The rear edge of the foot plate is adapted to engage a slot or opening 27 in the berth support or car wall, and the side edge adjacent to the side plate 26 engages a notch 28 25 in the bar 21. The bar is laterally enlarged below the notch, as shown in Fig. 1, to provide a firm support for the foot plate, and the upturned side plate 26, as well as the back plate 25, provides a firm and rigid support for the cushion 11. When the cushion 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270
